UNITED STATES PATENT OFFICE

EDWARD RATHBUN, OF TOLEDO, OHIO

FUEL DISTRIBUTOR FOR COMBUSTION ENGINES

Application filed May 6, 1929. Serial No. 360,715.

This invention relates to internal combustion engines, and more particularly to a device for distributing fuel oil from a single source to a plurality of cylinders, without the admixture of air. It has been common to effect such distribution through the medium of a rotary valve like member which registers successively with the lines leading to the various injection nozzles.

10 One of the objects of the present invention is to provide a simpler construction for this purpose. In its present embodiment, this involves the use of a rotatable continuously driven valve-like member which is so arranged that it may be intermittently subjected to the high pressure of the fuel without stopping the rotation of said member or causing injury thereto. The invention also includes various features of construction 15 which will be more particularly explained in connection with the accompanying drawings, illustrating one embodiment thereof.

In the drawings:

Figure 1 is a central vertical sectional view 25 of the invention.

Figure 2 is a section taken on the line 2—2 of Figure 1.

Figure 3 is a perspective view of the distributor valve detached.

30 As illustrated in the drawings, the invention is supported on a mounting 5 secured to a base 6. Secured to this mounting is a block 7, to which is secured a cup-shaped housing or head 8, providing a cylindrical chamber 9 within which a distributor valve 10 is mounted for rotation. Fuel oil is intermittently supplied under high pressure through the chamber 9 by the usual pump connected to a pipe line 11, leading to an 35 inlet port 12 located centrally of the head 8.

The valve 10 has a cavity 13 in its upper face extending beneath the port 12 and an outlet port 14 extends downwardly from this cavity through the valve to the valve seat 45 15, which is secured in the block 7 and on which the valve 10 rests. The valve seat 15 has a number of passageways 16 therethrough, with which the outlet 14 registers in turn as the valve rotates. It will be understood that there is one outlet passageway

16 for each cylinder to be supplied, and each of these passages leads through a passageway 17 in the block 7 to a line 18 connected with the cylinder.

The valve 10 is adapted to be continuously rotated by means of a vertical shaft 19, which extends upwardly through the base 6, the mounting 5, the block 7 and the valve seat 15 terminating within a cavity formed in the bottom of the valve. A pin 20 in shaft 19 engages a recess 21 in the valve and assures proper assembling of the valve in relation to the shaft. Thus the valve is positively driven by the shaft 19, but is permitted to have a very limited axial movement with respect to the shaft, within the chamber 9.

The drive shaft 19 extends through a sleeve 22 secured within the mounting 5, within which the shaft has a slight clearance. The upper portion of the shaft is reduced and extends through a chamber 23 in the block 7 and through the valve seat 15 within which it has a clearance as shown at 24.

As stated above, the shaft 19 and the valve 10 are adapted to be continuously rotated, and during this rotation the valve port 14 registers successively with the outlet passageways 16. The oil is intermittently supplied to the distributing chamber 9 and the cavity 13 under very high pressure, the pressure being created by an oil pump, as will be understood by those skilled in the art. The pump strokes are timed to take place during the period of registration of the valve port to the respective passages 16. The time of such registration is short, and the high pressure occurs only during the intermittent operation of the pump and is relieved during the subsequent movement of the valve to bring the port 14 into registry with the next

40 outlet passage 16. There is sufficient clearance between the valve and the wall of the valve chamber to permit the oil to work around the valve during high pressure and between the valve and its seat when the pressure is relieved. This causes a film of oil to be maintained at all times between the valve and its seat, thereby permitting a free rotation of the valve, since it is found in practice that the high pressure on the valve

is not maintained long enough to expel such film. The oil, as it continues to work underneath the valve during its operation, drains downwardly around the upper portion of the shaft into the chamber 23. A collar 25 carried by the shaft directs this oil into the annular space 26 surrounding the sleeve 22 whence it is discharged through the opening 27 and may be returned to the pump. In order to maintain the port 14 in communication with each passageway 16 for the desired length of time, the lower end of the port 14 may be elongated as shown at 28.

The distinctive feature of this invention is that a continuously rotating distributor valve may be used in engines in which the fuel is injected under extremely high pressure. This pressure may be directed against the valve without interfering materially with its rotation, provided the pressure is relieved for sufficient intervals to permit the lubrication of the valve seat in the manner described. In connection with this mode of operation, the extreme simplicity of the construction is of the utmost importance.

While I have shown and described in considerable detail the preferred embodiment of the invention, it is to be understood that this is merely for the purpose of illustration, and that various modifications may be made therein without departing materially from the scope of the invention as claimed.

What I claim is:

1. In combination, a pipe through which fuel oil is supplied intermittently under pressure, a valve seat, a constantly rotatable distributor valve arranged to be urged against said seat by pressure of the oil supply, a head within which the valve is confined, said valve being relieved from the head throughout the greater part of its inlet face and adjacent lateral surface, thereby permitting the oil to lubricate said seat between pressure impulses.

2. In combination, a valve seat having a number of ports, a fuel distributor valve continuously rotatable on said seat to uncover said ports successively, and a cup-shaped housing cooperating with said seat to form a valve chamber, said housing having a central inlet intermittently admitting fuel under pressure to the chamber on the side of the valve opposite to said seat, said valve being relieved from the housing for the greater part of its surface, thereby permitting oil to reach and lubricate said seat between pressure impulses.

3. In combination, a valve seat having a number of ports, a fuel distributor valve continuously rotatable on said seat to uncover said ports successively, a support for said valve seat, a continuously rotatable drive shaft extending upwardly through said support and seat and having a driving connection with the valve, a housing cooperating

with said seat to form a chamber for the valve, means for intermittently supplying fuel under high pressure to the chamber on the side of the valve opposite said seat, and means for supplying fuel oil as lubricant to said seat between pressure impulses.

4. In a fuel distributor, the combination of a valve seat having a number of ports, a fuel distributor valve continuously rotatable on said seat to uncover said ports successively, and a housing cooperating with said seat to form a chamber closely surrounding said valve, said housing having an inlet through which fuel is supplied intermittently under high pressure, said valve being relieved from the housing for the greater part of its surface, thereby permitting oil to reach and lubricate said seat between pressure impulses.

5. In a fuel distributor, a valve seat having a number of ports, a distributor valve continuously rotatable on said seat to uncover said ports successively, a support for said valve seat, a continuously rotatable drive shaft extending upwardly through said support and seat and having a driving connection with the valve, a housing cooperating with said seat to form a chamber closely surrounding the valve, said housing having an inlet for admitting fuel intermittently under high pressure on the side of the valve opposite said seat, said valve being relieved from the housing for the greater part of its surface, thereby permitting oil to reach and lubricate said seat between pressure impulses.

6. In a fuel distributor, a valve seat having a number of ports, a fuel oil distributor valve continuously rotatable on said seat to uncover said ports in turn, a housing cooperating with said seat to form a chamber closely enclosing the valve, a drive shaft having a driving connection with said valve, means for introducing fuel oil intermittently under high pressure to said chamber on the side of the valve opposite to said seat, said valve being relieved from the housing for the greater part of its surface, thereby permitting oil to reach and lubricate said seat between pressure impulses.

In testimony whereof I have hereunto signed my name to this specification.

EDWARD RATHBUN.
